UNITED STATES PATENT OFFICE

163,102

JEWELLED EAR MUFF

Jean Brownlee Dolton, Hazardville, Conn.

Application November 28, 1950, Serial No. 13,163

Term of patent 7 years

(Cl. D3—2)

To all whom it may concern:

Be it known that I, Jean Brownlee Dolton, a citizen of the United States of America and a resident of Hazardville, in the county of Hartford and State of Connecticut, have invented a new, original, and ornamental Design for a Jewelled Ear Muff, of which the following is a specification, reference being had to the accompanying drawing, forming part thereof.

In the drawing:

The dotted line figure of the wearer shown in Fig. 1 is included merely for purpose of illustration.

I claim:

The ornamental design for a jewelled ear muff, as shown and described.

JEAN BROWNLEE DOLTON.
